UNITED STATES PATENT OFFICE

2,635,202

AUTOMOBILE IGNITION DEVICE

Henry O. Striker, Detroit, Mich.

Application February 19, 1951, Serial No. 211,783

1 Claim. (Cl. 313—45)

1

This invention relates to an improved electrical device adapted to be introduced into the electrical ignition circuit of an internal combustion engine to improve the operation thereof.

An important object of this invention is to provide a voltage amplifying device which is capable of economical manufacture and which is composed of a few simple parts designed for rapid assembly. Another important object of the invention is to provide a device of this character which is readily installable in the ignition circuit of an internal combustion engine without alteration of the existing construction thereof. A further important object of the invention is to provide a device of this character having certain inner parts thereof constructed and arranged in a novel manner to form an electrical jump barrier.

In carrying out the invention, a housing in the form of a cylindrical casing of insulative material is provided. The casing is closed at one end and the closed end is provided with an exposed electrical terminal or contact projecting into the hollow interior of the casing. The opposite end of the casing is closed by a removable plug member shaped to receive a lead wire of the ignition circuit and provided with an electrical terminal or contact which projects into the hollow interior of the casing. Positioned in the hollow interior of the casing are certain elements which cooperate together to provide an electrical jump barrier. These parts include a series of alternately electrically conductive and non-conductive disc-like elements abuttingly engaging one another. Located in the hollow interior of the casing is a coiled spring which holds the disc-like elements in intimate contact with one another and also serves as a conductor for electrically connecting the series of discs with one of the terminals. Also included in the structure is a carbon block electrically connected to the other terminal and to the opposite end of the disc series.

Various other objects, advantages and meritorious features of the invention will become more fully apparent from the following specification, appended claim and accompanying drawings, wherein:

Fig. 1 is a vertical longitudinal sectional view taken through the device and illustrating in dotted outline the connection of the device to conventional parts of the ignition circuit, and

Fig. 2 is an exploded view of the parts of the device showing same in perspective and in their order of assembly.

2

The structure in its preferred form comprises a substantially cylindrical housing or casing 10 of electrically insulative material having a closed end wall 12. The opposite opened end of the casing is closed by a removable plug member 14 of electrically insulative material. The member 14 cooperates with the side walls of the casing and the closed end wall 12 thereof to form a chamber in the casing. The inner wall surface of the casing 10 is formed of two slightly different diameters to form a shoulder 16 against which the inner end of the plug member 14 abuts. The exterior dimensions of the plug member 14 are such that it frictionally engages the inner wall of the casing 10 and is held from accidental dislodgement therefrom.

The bottom end wall 12 of the casing is provided with an outwardly projecting terminal for contact with a part of the ignition circuit such as the spark plug indicated in dotted outline at 18 or the terminal on a distributor to which a high tension line from the coil is normally connected. The electrical contact is preferably a split sleeve 20 as indicated in Fig. 2 threaded on a bolt 22 fixed to the closed end 12 and its head 24 is located in the chamber to serve as an electrical contact. A nut 26 threaded on the bolt serves to tightly secure the contact bolt in place.

The removable plug closure member 14 is provided with an outwardly opening axial bore 28 which serves as a socket for receiving a lead wire indicated in dotted outline at 30. The base end of the socket 28 is provided with an electrical contact member in the form of a rivet 32 which extends through the balance of the plug and projects into the chamber formed by the casing.

Positioned in the upper part of the chamber of the device is a coiled spring 34, the major portion of which has a cylindrical formation as shown in Fig. 2 but one end thereof is spirally formed as at 36 to abut the closure member 14 and to contactually surround the projecting end of the terminal 32. The spring is composed of electrically conductive material and serves as a conductor in the operation of the device.

Located in the lower part of the chamber of the device is a carbon block 38 shaped to slidingly fit the interior of the casing 10. The carbon block 38 may be provided with a recess 40 for receiving the head 24 of the bolt 12. However, the recess is so designed that the carbon block is brought into electrical contact with the head of the bolt in the final assembled position of the parts.

55 Located in the central part of the chamber

and positioned between the spring 34 and the carbon block 38 is a series of separate disc-like elements alternately composed of electrically conductive and non-conductive materials. One alternate set of discs in the series is formed of copper or like electrically conductive material. These discs are indicated at 42 in the exploded view of Fig. 2 and are relatively thicker than the remaining discs of the assembly. The remaining alternate set of discs are preferably formed of mica or similar electrically insulative material and are indicated at 44 in Fig. 1. The mica discs are perforated, preferably in alignment with one another. The perforations are preferably circular apertures 46 on the axis of the casing 10. The mica disc elements and their respective apertures provide electrical jump barriers between the copper discs 42 with which they are interleaved.

For the purpose of dissipating the heat which may be generated during the operation of the device, a coil wire 48 is mounted in encircling relationship around the closure plug 14. The opposite ends of the heat dissipating coil lead through the plug to the chamber in the manner shown at 50 in Fig. 2. The heat dissipating coil is preferably mounted on the closure plug by forming a peripheral groove 52 on the outside surface thereof as shown in the drawing.

There is provided as the result of this invention, a small compact device for improving the operation of internal combustion engines. The device is interiorly constructed to insure physical contact of the assembled elements at all times and under all conditions.

What I claim is:

A device for use in the ignition circuit of an

internal combustion engine comprising, in combination, a hollow cylindrical casing of insulative material closed at one end, a removable plug member closing the opposite open end of said casing and cooperating with the closed end to form a sealed chamber therebetween, said plug member having an outwardly opening socket for receiving a wire lead of the ignition circuit and provided with an electrical contact in the socket projecting into the chamber, said closed end of the casing provided with an exposed electrical contact extending through the end wall of the casing and projecting into said chamber, a plurality of discs of alternately electrically conductive and electrically insulative materials arranged in a connected series in said chamber, a coiled spring in said chamber interposed between said series of discs and the plug closure and serving as an electrical connection between the discs and said terminal, said alternate discs of insulated material being perforated to provide jump barriers between the electrically conductive discs of the series, and a coiled wire carried exteriorly by the removable plug member and encircling the same for dissipating heat generated during the operation of the device.

HENRY O. STRIKER.
